UNITED STATES PATENT OFFICE.

LEILA M. JOHNSTON, OF COLEMAN, TEXAS.

PROCESS OF MAKING ROUND-BOTTOMED PAPER BAGS.

1,127,258.

Specification of Letters Patent.

Patented Feb. 2, 1915.

Application filed April 7, 1914. Serial No. 830,213.

To all whom it may concern:

Be it known that I, LEILA M. JOHNSTON, a citizen of the United States, residing at Coleman, in the county of Coleman and State of Texas, have invented certain new and useful Improvements in Processes of Making Round-Bottomed Paper Bags; and I do hereby declare the following to be a full, clear, and exact description of the invention, such as will enable others skilled in the art to which it appertains to make and use the same.

This invention relates to processes of making round-bottomed paper bags and one of the principal objects of the same is to provide a paper bag which can be made of two pieces, which can be quickly assembled to form the bag, and in which the process of manufacture and the labor involved will be economical, and in which there will be no waste paper.

Another object of the invention is to provide an economic process or method of forming paper bags which will be economical both in the saving of stock and labor and which will produce a very superior paper bag for many purposes.

These and other objects may be attained by means of the construction illustrated in the accompanying drawing, in which,

Figure 1 is a horizontal sectional view taken on the line 1—1 of Fig. 2, Fig. 2 is a side elevation and partial section of the lower end or bottom of the bag, and Fig. 3 is a detail sectional view of a slightly modified form of the invention, showing a reinforcing band encircling the bag at the bottom.

Referring to the drawing, the numeral 1 designates the tubular portion or body of the bag and 2 is the round bottom thereof. An upwardly turned annular flange 3 is formed on the bottom 2 and this flange is inserted within the bottom of the body portion 1 of the bag and secured by a suitable adhesive substance like paste. In carrying out the method or process of making paper bags in accordance with this invention a circular form of the required size is provided and a strip of paper is cut of suffi-

cient length and width to extend around the form and to be connected by overlapping edges as at 4. The tubular blank is then removed from the form or mandrel and cut into the length desired for the bag. 55 The bottom 2 is formed by cutting a number of disks of the required size from the paper and bending up the flanges 3 of a size or diameter to fit nicely within the tubular portion 1 of the bag. The tubular 60 portion 1 is then inserted on a form and the bottom 2 is placed on top of the form and the tubular portion is then drawn upward and connected to the flange 3 by an adhesive substance, after which the bag is 65 dried.

There are many advantages in the use of a round bottomed paper bag. Many articles sold in the general market are of cylindrical form, like can goods for instance 70 and a circular bag to inclose such articles furnish a neat package and are more readily utilized for its purpose. Another advantage of a paper bag made with a round bottom and in which the flange of the bottom is inserted within the end of the tubular portion, resides in the fact that granular material like flour, sugar and similar pulverized or granular material will not gather around the corners as is the case in 80 the ordinary regular paper bags, and when it is desired to empty the contents of the bag every particle can be quickly emptied out, since there are no nooks or corners to conceal portions of the granular material. 85

As shown in Fig. 3, a reinforcing band 1^a surrounds the bag at the bottom, and said band extends up even with the upper edge of the flange 3 of the bottom. The lower edge of the reinforcing band 1^a is 90 flush with the bottom.

What is claimed is:—

A method of making paper bags which consists in forming a long paper tube, securing the overlapping edges of the tube 95 together by an adhesive substance, cutting the tube into suitable lengths, cutting out a number of circular blanks for the bottoms of the bags, turning up a flange around the blanks, applying an adhesive substance to 100

the bent-up flange, connecting the tubular body portion to the flange of the bottom with the edge of the body portion lying flush with the bottom, and securing by an adhesive substance, a reinforcing band outside the bag with its lower edge flush with the bottom.

In testimony whereof I affix my signature in presence of two witnesses.

LEILA M. JOHNSTON.
